VOTING MACHINE

Alvin N. Gustavson, Jamestown, N. Y., assignor to
 Automatic Voting Machine Corporation,
 Jamestown, N. Y., a corporation of Delaware

Application April 5, 1940, Serial No. 328,060

10 Claims. (Cl. 235—54)

This invention relates to an improvement in voting machines and more particularly to a mechanism for nullifying improperly cast ballots.

In elections for representatives to general assembly, representatives to conventions, or other office groups, there are more candidates seeking nomination or election than there are offices to be filled. It has been found that a minority group of voters, by prearrangement, could in part at least defeat the purposes of an election pertaining to office groups by casting ballots for a lesser number of candidates than the number of offices in a given office group, and laws have, therefore, been enacted to prevent such practice. These laws state in substance that, that portion of a voter's ballot relating to office group elections is invalid if he has failed to indicate his preference for the same number of candidates as there are offices in a given group. Voting machines have, therefore, been so arranged that a voter could not register his ballot without first complying with the above mentioned laws. In some elections there are candidates seeking nomination or election to other offices as well as those of an office group, and a voter, having properly indicated his ballot with respect to these, would thus be prevented registering any part thereof if he fails to comply with the requirements in connection with balloting for candidates in an office group.

It is the purpose of the present invention to provide a mechanism for a voting machine that will nullify all improperly cast ballots, including those for candidates in one or more office groups, without affecting the voter's ballot with respect to other candidates, and this therefore constitutes one of the objects of the invention.

Another object of the invention lies in the provision of a mechanism for a voting machine that serves to return certain candidate indicators to non-voting position during the operation of registering other indicated votes.

Another object of the invention lies in the provision of a mechanism that operates to prevent a voter from retracting a properly indicated ballot at any time during the operation of registering the ballot and returning the indicators to non-voting position.

Another object of the invention lies in the provision of a mechanism for a voting machine that is operable to return certain of the voting indicators to non-voting position at commencement of the registering operation, when a voter has failed to comply with such voting require-

ments as the mechanism is capable of controlling.

Other and further objects of the invention will be more fully understood from a consideration of the following specification taken in conjunction with the accompanying drawings, and in which

Figure 1 is a somewhat diagrammatic perspective view taken from the rear of a voting machine disclosing one form of the invention and its operative connection with a vote registering lever;

Figure 2 is an enlarged rear elevational view of the invention as applied to a voting machine and shows the position assumed by the movable parts when the vote registering lever is in the position shown in full lines in Figure 1;

Figure 3 is a fragmentary plan view of the structure shown in Figure 2;

Figure 4 is a substantially full size end view of the invention as applied to the main interlock of a voting machine, being taken substantially as indicated at 4—4 of Figure 2;

Figure 5 is a fragmentary elevational view of the structure that serves to actuate the invention, showing the position of the parts when the vote registering lever is near the dotted line position of Figure 1;

Figure 6 is a view of the mechanism similar to that of Figure 4 and shows the position assumed by the movable parts during the period of registering a properly cast ballot;

Figure 7 is a further end view of the mechanism showing the position of the parts during the operation of retracting improperly cast ballots;

Figure 8 is a fragmentary plan view illustrating the position of certain of the parts when a voter has complied with the requirements concerning balloting in a given office group; and

Figure 9 illustrates the method of assembling certain parts of the mechanism.

It will be understood that the present invention is directed generally to the subject matter of my co-pending application, Serial No. 302,575, being a continuation in part thereof and provides, however, improved structure and additional safeguards for the proper balloting in elections involving the nomination or election of candidates to various office groups. To this end the mechanism of the invention is arranged to permit a voter's indicating his preference for the same number of candidates as there are offices to be filled, at the same time allowing him to alter his choice until such time as he desires

to register his ballot and leave the voting machine. The mechanism additionally provides means for preventing a voter, who has complied with the office group requirements, from retracting part of his ballot once he has commenced movement of the operating lever through the ballot registering and indicator returning cycle.

Reference is now had particularly to Figure 2 of the drawings wherein the numeral 10 is employed to generally designate the invention which, in its present form, includes an interlock 11 that, as shown in Figure 4, is auxiliary to a main interlock 12. The interlock 11 comprises a pair of spaced vertical plates 13 and 14 that are suitably connected by spacer blocks 16. Projecting vertically through the blocks 16 are rods 17, to the lower ends of which are fitted bases 18. A spring 19, encircling each rod 17 between blocks 16 and base 18, serves to yieldingly extend the rod to a limit determined by a pin 21. Adjacent the ends of plate 14 are laterally projecting lugs 22 having upwardly opening slots 23 that engage the under edge of the front plate of the main interlock 12. The structure described serves to mount the interlock 11 at any desired position along the length of the main interlock 12.

The interlock 11 is of a form similar to that shown and described in my Patent 2,110,297 and includes rollers 24, the enlarged ends of which are seated in channels 26 of the plates 13 and 14. At one end of the interlock 11 is a shoe 27, the sides of which are located in the channels 26. A grouping pin 28 may be projected through a pair of aligned openings 29 in the plates 13 and 14, as well as a specially designed apertured roller 30 for the purpose of preventing movement of a predetermined group of rollers 24 in a direction other than toward the shoe 27 (see Figure 8).

Projecting away from the plate 13 are pins 30 that may be fitted with spacer collars or washers 31. A member 32 is adapted to be mounted on the plate 13. This member is formed with depending arms 33 and 33a centrally of which are rectangular slots 34. The lower ends 35 of these arms are bent inwardly in a manner substantially as indicated in the drawings and compensate for the thickness of washers 31. The arm 33a is formed with a shoulder 36. Between arms 33 and 33a and also forming a part of member 32 is an arm 37 that is of a length and position corresponding to the shoulder 36, being adjacent the other end of the mechanism. A pair of lugs 38 project outwardly from the plate 13 of the interlock. The pins 30 project through the slots 34 and are of a diameter substantially half the width of the slots. Any conventional means, such as washers and cotter pins, serve to loosely mount the member 32 on pins 30 for movement thereof to the extent limited by the size of slots 34. Generally centrally of the member 32 is a depending strap 39 that is formed at its lower end with a horizontally disposed lug 40. This lug projects through a slot 41 in the lower edge of plate 13, the relative width of lug and slot being comparable to that of pin 30 and slot 34. On the inner face of the plate 14 is a pin 42. A spring 43 is secured at its ends to lug 40 and pin 42, the position of the spring being such that it normally urges the member 32 slightly upwardly to the right, as viewed in Figure 2 of the drawings. It is to be noted that movement of the member 32 to the left causes the lower edge of arm 37 and shoulder 36 to overlie lugs 38 when said member

is in its uppermost position and, under such circumstances, said member cannot be depressed.

For convenience of assembly the member 32 is in two parts and includes a bar 44 that is formed with vertical and horizontal flanges 45 and 46. This bar is adapted to be mounted on and secured to the member 32 in any suitable manner. Two or more rotatable pins 47 are mounted on the outer face of the body of the member 32 and are formed with narrow heads. Openings 48 are made in the flange 45 of bar 44 and are of a shape to receive the heads of the pins 47. When the pins have been projected through the openings they may be rotated to assume a position at right angles to the openings 48 and thus secure the bar to the member. Adjacent the ends of the bar 44 laterally directed lugs 49 are provided. Adjacent lugs 49 are cams 50. The purpose of the lugs and cams 49 and 50 will herein-after be more fully set forth. At one end of the member 32, optionally integral therewith or with bar 44, is a horizontal flange 51 that terminates in a depending strap 52. The strap 52 projects into the open end 53 of the shoe 27.

It is common practice in interlocks, such as indicated by the numeral 12, to provide a number of straps 54 having enlarged ends 55 that project between pairs of rollers 57. These straps include lugs 58 to which the upper ends of auxiliary straps 61 may be attached. The auxiliary straps 61 are formed at their lower ends with enlarged portions 62 that project between pairs of rollers 26. A short space above the end 62 each strap is formed with a laterally directed lug 63, the lower edge of which may be slightly beveled. Spaced slightly above the lug 63 is a pointed lug 64 that is provided with a small flat shoulder 65. When the interlock 11 is assembled both lugs 63 and 64 are beneath the flange 46 of bar 44, substantially as indicated in Figure 4 of the drawings.

While it is unnecessary to describe the operation and parts of interlocks to which the present invention is applicable, it is pointed out that each strap 61 is connected with a voting indicator on the face of the voting machine through a strap 54, or in any other suitable manner, and that when an indicator is operated the corresponding auxiliary strap 61 is moved upwardly separating a pair of rollers 24 as the enlarged portion 62 projects between said rollers. This lateral displacement of the rollers can be only in the direction of shoe 27, since grouping pin 28 prevents movement in the opposite direction (see Figure 8).

Secured to the frame of the voting machine and located adjacent one end of the auxiliary interlock 11 is an upstanding bracket 66. A laterally directed arm 67 mounts one end of a shaft 68 that, as indicated in the drawings, parallels the interlock 11. This shaft may extend the full length of the machine and be supported at the other end by a further arm, not shown. In the present disclosure of the invention two arms 69 are mounted on the shaft 68. These arms extend laterally toward and into close proximity with the flange 45 of bar 44. Each arm includes an upper portion 70 and a downwardly offset finger 71. The finger is bent to be slightly out of vertical alignment with the portion 70. A pin on the portion 70 mounts a roller 72. The arms 69, of which there are as many as may be required for lugs 49, are clamped to the shaft 68 in any suitable manner and are adjustable along the shaft to be aligned with the lugs 49 at whatever position the

interlock 11 may be mounted on the main interlock 12.

Adjacent the supporting arms 67 the shaft 68 carries a further arm 73 that is pivotally joined to one end of a twist link 74. The other end of this link is pivotally joined to an arm 76 of a bell crank 77, pivotally mounted on the upper end of bracket 64. The bell crank includes a further arm 78 to the end of which is fitted a laterally directed pin 79. A vertically disposed bar 81 terminates adjacent the bracket 66 in an enlarged end 82, in which is formed slots 83 and 84. Slot 83, as indicated in Figures 2 and 5 of the drawings, is vertical and receives a pin 86 secured to the bracket 66. Suitable means is provided to prevent lateral displacement and disengagement of pin 86, and this structure serves merely as guide means for vertical reciprocation of said bar. Slot 84, as indicated in Figures 2 and 5, is of substantially the same length as slot 83 but located slightly thereabove. Approximately the upper half of the length of this slot is vertical and parallel to slot 83. Midway of its length, however, slot 84 is laterally inclined, as indicated at 87. From the inclined portion 87 the slot has a short, straight portion 88 that terminates in a portion 89. It will be noted the portion 89 is in the same vertical plane as the straight upper end of the slot. As the bar 81 is moved vertically upwardly a distance governed by the length of slot 83, pin 79 follows the contour of slot 84 throughout its length and in so doing bell crank 77 is moved from the position of Figure 2 to that of Figure 5 and again back to that shown in Figure 2. This motion of the bell crank rotates shaft 67 and arms 68 first in a clockwise and then in a counter-clockwise direction, as viewed in Figure 4. The extent of movement of arms 69 is indicated by a comparison of Figures 4 and 6.

As is more or less diagrammatically indicated in Figure 1, the bar 81 is connected through conventional linkage with a voting machine operating lever 91. With the lever 91 in the position shown in Figure 1, the bar 81 is in the position shown in Figure 2 and the voting machine is locked against use. However, when the lever 91 is moved to the dotted line position, the linkage causes bar 81 to move upwardly and in so doing the bell crank, as already indicated, is rotated out of and again into the position shown in Figure 2.

Having described the structure of the invention, operation thereof is as follows. For purposes of illustration it is assumed that the voting machine to which the present invention is applied is to be used in connection with casting ballots for office group candidates and that there are ten candidates up for nomination or election to five offices. Figure 8 of the drawings indicates this set up and it is to be noted that ten of the straps 61 are interposed between pairs of rollers 24. These straps, as already set out, are connected with voting indicators of the nature shown in my Patent 1,948,660. As the indicators are manipulated the straps will be moved from the position of Figure 4 to that of Figure 6. It will be noted that the pointed lugs 64 of the straps are of insufficient size to merely contact the edge of flange 46 as the straps are raised, but that the lug 63 contacts this flange and determines the extent of upward movement of the straps (see Figure 6). When five of the straps 61 have been raised as described, rollers 24 of the interlock 11 will have been moved laterally to contact and move shoe 27 to the left, as viewed

in Figure 8. Inasmuch as the shoe 27 is in contact with the depending strap 52 of the bar 44 and the bar 44 is a permanent part of the member 32, said member will be moved laterally to the left, as viewed in Figure 2, the extent of movement being determined by pins 30 and slots 34. Shoulder 36 and arm 37 of the member 32 now overlie lugs 38 and, since this member is in elevated position, it cannot be lowered until again being laterally moved. With the member 32 in this position, lugs 49 have been removed from directly beneath the portions 70 of arms 69. However, rollers 72, being of greater width than the portions 70, still in part overlie cams 50 (see Figure 8). As has been mentioned, one of the purposes of the invention is to prevent a voter, who has made his selection of the required number of candidates in an office group and commenced registering such selection, from changing or retracting any part of this selection. The operating lever, being in the dotted line position of Figure 1, is moved toward full line position. On the first movement of the lever in this direction, bar 81 moves a sufficient distance to cause pin 79 to move into the portion 88 of slot 84, thus rotating arms 77 and depressing arms 69. As these arms move downwardly, portions 70 clear lugs 49 but rollers 72 contact cams 50 and tip the member 32 inwardly to the extent that the edge of flange 46 abuts the body of each of the voted straps 61 directly above the lugs 63. The arms 69 hold member 32 in this position only for the period represented by the length of the portion 88 of slot 84. However, during this period the registering mechanism of the voting machine has acted and the ballot cannot be changed. If a voter, during the operation of moving the lever 91 from dotted to full line position, should attempt to retract one of the straps 61, the shoulder 65 of lug 64 would contact the edge of flange 46 of the member 32 and, since this member is not depressible, due to its position with respect to lugs 38, none of the actuated straps can be moved. However, as the lever 91 is further moved toward full line position of Figure 1, bar 81 moves downwardly and pin 79, following the incline 87 of slot 84, rotates bell crank 77, thus raising the arms 69 to the position of Figure 4. The flange 46 is thus withdrawn from contact with the straps 61 and from beneath shoulders 65. Straps 61, by a conventional mechanism of the voting machine, are returned to the inoperative position shown in Figure 4. When the straps 61 are returned, the spring 43 becomes effective to laterally return the member 32 to the position of Figure 2. Any tendency on the part of lugs 64, as they pass flange 46, to depress the member 32 is counteracted by the fingers 71 of arms 69, since these fingers, when the member 32 has been returned by the spring 43, are in contact with the under surfaces of lugs 49.

The above described operation of the invention assumes that a voter has properly cast his ballot in the office group under consideration. Operation of the invention, when a voter has improperly cast his ballot, is as follows. It is assumed a voter has actuated only two of the five required indicators in an office group. Thus only two straps 61 will have been raised, and since there is sufficient play between the rollers 24, these rollers will not have moved shoe 27. As shoe 27 normally serves to move member 32, this member remains in the position shown in Figure 2. Under these circumstances, when a voter moves the operating lever 91 from dotted to full

line position, the bell crank 77 will be immediately rotated to depress arms 69. Portions 70, being directly over lugs 49, will, by contact therewith, move member 32 vertically downwardly and in so doing flange 46, by reason of its contact with lugs 63, will return the straps 61 to non-voting position. It is to be understood that the return of these straps to non-voting position is so timed during the cycle of registering a vote that the registering operation does not commence until after the straps have been returned. It will be noted that rollers 12 are not in vertical alignment with the cams 50 and, consequently, the member 32, under these circumstances of operation, is not tilted. Figure 7 of the drawings clearly indicates this movement of the parts.

Inasmuch as the mechanism of the invention functions just in advance of the registering mechanism of the voting machine, it serves to test the correctness of an office group vote and, if correct, secure the vote until registering has taken place, and if incorrect, return the indicators to non-voting position.

It will be understood that the invention has been applied to office group voting primarily for purposes of illustration and that the structure thereof is applicable, in its present or modified form, to other voting requirements wherein it is necessary to maintain the parts in the position of correct balloting or to nullify any part of an incorrectly cast ballot, and that such adaptations or changes in the structure are contemplated insofar as they are within the spirit and scope of the invention as defined in the hereunto annexed claims.

Having thus set forth my invention what I claim as new and for which I desire protection by Letters Patent is:

1. In a voting machine having members movable to an operated position and a lever operable through other mechanism to move said members to inoperative position, straps individually connected with and operable by said members, a bar movable to engage the straps of any members moved to operated position, means operably connecting said bar with said lever in such a manner as to render said bar operable by movement of said lever to engage and restore said straps and the members connected therewith, and further means actuated by movement into operated position of a predetermined number of said straps rendering said bar effective only to hold said straps and said members in operated position.

2. In a voting machine having members movable to an operated position and a lever operable through other mechanism to restore said members to unoperated position, a mechanism having straps connected with said members, means in said mechanism adjustable to effect holding a predetermined number of said straps and said members in operated position, said means being additionally movable to restore all straps to unoperated position if less than the predetermined number have been operated and further means having connection with and being operable by said lever to both adjust and move said means.

3. In a voting machine having straps movable to an operated position and a lever operable through other mechanism to restore said straps to unoperated position, a first means associated with said straps and operable thereby, further means associated with said straps and normally operable to restore any less than a predetermined number of operated straps to unoperated posi-

tion, said first means being actuatable by movement of said predetermined number of straps into operated position to render said further means inoperative to restore the operated straps to unoperated position, and additional means operable by said lever to actuate said further means to hold said predetermined number of straps in operated position during a part of the movement of the restoring operation of said lever.

4. In a voting machine having vote indicating members movable to indicating position and a lever operable through other mechanism to move said members to non-indicating position during a voting cycle, an interlock, straps operably connecting a group of said members with said interlock, means on said interlock engageable with and in a manner to secure said straps in operated position, strap actuated means for conditioning said means for subsequent movement into engagement with said operated straps, and linkage for effecting movement of said means by said lever during part of a voting cycle.

5. In a voting machine having vote indicating members movable to indicating position and means operable to restore said members, an interlock, straps operably connecting a group of said members with said interlock, a tiltable bar on said interlock, strap actuated means to condition said bar for movement into engagement with any of said straps in operated position, and additional means providing operable connection of said bar and the member restoring means, said bar, during part of a voting cycle, being tiltable by said restoring means to engage said straps in such a manner as to secure them against operation.

6. In a voting machine having vote indicating members movable to indicating position and a lever operable to move said members to non-indicating position, straps connected with and operable individually by any of a predetermined number of said members, a bar movable to engage and move any of said straps and the members connected therewith from indicating to non-indicating position, strap actuated means to condition said bar for subsequent movement to engage and hold the straps against movement at one time, and an arm linked with and operable by said lever to engage said bar with and move said straps at another time.

7. In a voting machine having members movable to an operated position and a lever operable through other mechanism to restore said members, straps connected with and operable by said members, control means associated with said straps, means operable, by movement of a predetermined number of said straps into an operating position, to render said control means operable, by said lever, to momentarily engage and hold said straps in operated position, said means being operable by less than said predetermined number of straps to render said control means operative by movement of said lever to restore said operated straps to inoperative position, and means operatively connecting said control means with said lever.

8. In a voting machine having members movable to an operated position and other mechanism operable to restore said members to unoperated position; a mechanism having straps connected with said members, means carried by said mechanism operable to effect holding said straps in either operated or unoperated position, strap actuated means to condition said means to engage and hold said straps, said first means having

connection with and being operable by said other mechanism during at least a part of the restoring operation.

9. In a voting machine having members movable to an operated position and other mechanism operable to restore said members to unoperated position; a mechanism having straps operably connected with said members, strap actuatable means, other means associated with said mechanism and rendered operable by said strap actuatable means upon movement of less than a predetermined number of said members to engage all of said straps and hold them against movement relative to said other means, and further means having operable connection with said other mechanism for actuating said other means to return said operated straps and members to unoperated position.

10. In a voting machine having a group of

5 indicators and straps coupled therewith and adapted to be moved thereby and restoring means adapted by said straps, a member conditioned by said strap actuated means to restore to non-indicating position any of said indicators when a number less than a predetermined number of said indicators have been operated, said strap actuated means, upon actuation of said predetermined number of indicators, rendering said member inoperative to restore said indicators and operative to hold said straps against movement by the associated indicators, and means operable by said restoring means to operate upon said member to effect the restoration of a number of straps and indicators less than said predetermined number.

ALVIN N. GUSTAVSON.
